APPARATUS

Crawford Hallock Greenewalt, Wilmington, Del., assignor to E. I. du Pont de Nemours & Company, Wilmington, Del., a corporation of Delaware

Application March 28, 1939, Serial No. 264,535

2 Claims. (Cl. 18—8)

This invention relates to the production of 5 yarns, filaments, ribbons, and the like by the melt spinning of organic filament-forming compositions. For convenience, but with no intention of so limiting this invention, it will be discussed in terms of the melt spinning of fiber-forming synthetic linear polyamides (super-polyamides) such as may be prepared by the condensation reactions described in U. S. Patents Nos. 2,071,250, 2,071,251, 2,071,253 and 10 2,130,948. For convenience, these fiber-forming synthetic linear polyamides are hereinafter referred to as polyamides.

The melt spinning of such compositions is a 15 new art and presents many problems since it is necessary not only to operate continuously, efficiently, and economically but also to produce products of very uniform properties, particularly in the case of textile yarns where uniform 20 denier, uniform dye affinity and uniform physical properties are very important.

A besetting problem in the operation of a plant 25 for the melt spinning of a textile yarn arises from the necessity of heating the melting and spinning apparatus to a high temperature before the actual spinning operation can be started and the high temperature at which the apparatus must be maintained throughout the spinning operation. The problem is presented by 30 the time required to put the spinning apparatus into service, to take it out of service, to effect repairs and/or change of production. It is necessary to carefully maintain the apparatus at these high temperatures with little variation. 35 This is conveniently done by providing a suitable melting unit and by jacketing the apparatus and passing a fluid heating medium through tubular heating coils in the melting unit and jacket. High pressure steam or Dowtherm 40 (a mixture of diphenyl-diphenyl oxide) may be used as the fluid heating medium. Electric coils may be substituted for the heating coils.

It is often necessary to change the denier 45 and/or filament count of the production, or to repair or adjust a spinning cell because of a defect in some part or operation. When this is necessary, the spinning apparatus must go out of service for a sufficient time for it to come to room temperature and permit mechanics to work 50 on it. Because of the compactness of the design of a commercial spinning plant, the overhauling of the spinning cell in its position interferes with the operation of adjoining apparatus and is likely to result in the production of inferior 55 yarn in adjacent positions. Finally after the

overhaul is completed, it becomes necessary to heat the melting and spinning apparatus for a long period of time before it again reaches an operative temperature and can again be put back into production. This problem of lost time and interference with normal operation has been 5 found very objectionable.

It is, therefore, an object of this invention to provide an improved process and apparatus for the continuous production of filaments, yarns, 10 ribbons and the like by the melt spinning of organic filament-forming compositions.

It is a more specific object of this invention to provide a combined melting and melt spinning apparatus in which changes in the melting or 15 spinning units, or repairs to these units, can be made without interrupting the spinning at any spinning position for an objectionable period of time.

Other objects of this invention will hereinafter 20 become apparent.

In accordance with the present invention, the above-mentioned objectionable delays and interruptions can be avoided by combining a melting unit and spinning unit in a single assembly 25 which may be interchangeably removed from and connected to a heating shell fixed in a spinning position, as well as to an auxiliary heating shell which is adapted to heat the melting and spinning assembly to operating temperature. 30

The practice of the invention will become more apparent by reference to the following description and the accompanying illustrations, in which:

Figure 1 is a cross-sectional view of an apparatus illustrative of this invention. 35

Figure 2 is a side elevational view, with parts shown in section, of the apparatus shown in Figure 1 with the melting and spinning assembly removed from the heating shell.

The spinning apparatus shown in Figure 1 comprises two parts, that represented generally by 1, which is a heating shell, and that represented generally by 2, which is a removable melting and spinning assembly.

The heating shell 1 comprises a rigid shell 4, tubular heating coils 6, and insulating material 8. The coils 3 are supplied with a heating medium such as super-heated steam or Dowtherm by means of inlet pipe 10 and outlet pipe 12. 50 The heating shell 1 is fixed in the spinning position base 14. The base 14 and the shell 1 are provided with an opening 16 for the pump drive shaft 18 which can be uncoupled from the metering pump of the spinning assembly and be with- 55

drawn from the base and shell. The rigid shell 4 is provided with a flange 20 containing holes to receive bolts 22 of the melting and spinning assembly for rigid mounting of parts 1 and 2 with each other. An opening is shown at 24 for the withdrawal of the spun yarns.

The melting and spinning assembly 2 comprises a hopper 30 for the solid flakes of filament-forming composition, a melting unit 32, a container 34 for molten composition, a metering pump 36, and a spinning unit 38. Flakes of filament-forming composition may be passed into hopper 30 through opening 40. While in operation the opening 40 is closed by cover 42. The top of hopper 30 is provided with eye bolts 44 by means of which the melting and spinning assembly may be lifted. The hopper 30 is connected to the frame 48 by means of bolts 46. The heating or melting unit comprising coil 32, encased in insulation 50, is positioned between the connecting flanges of the hopper 30 and frame 48. The insulation 50 prevents the hopper 30 from reaching an elevated temperature and prematurely melting the solid filament-forming composition. The melting unit 32 may be heated by the passage of a hot fluid through the inlet 52 and the outlet 54. The molten filament-forming composition drains from the melting unit and collects in a pool in container 34 which is connected to frame 48, for example, by welding. The container 34 is connected to the metering pump 36 which is adapted to meter the molten material to the spinning unit 38. The metering pump 36 is driven by the drive shaft 18 which is adapted to be positively engaged to the pump mechanism by coupling 56. The spinning unit 38 is connected to pump 36 by conduit 58. The spinning unit 38, including spinneret 60, and the pump 36 are all held firmly in place by means of annular plate 62 which is fastened to flange 64 of frame 48 by means of bolts 66. A gas inlet is shown at 70 and outlets at 72 and 74 to permit the maintenance of an inert atmosphere in the hopper and above the melting unit, and to remove any air or volatile impurities introduced with the solid filament-forming composition.

In the operation of this invention, the removable melting and spinning assembly 2 is mounted in a heating shell similar in construction to that shown at 1 but mounted in an assembly room. Solid flakes of the polyamide are introduced into the hopper 11 through the opening 40 after which the cover 42 is replaced. The flakes form a solid column resting on the melting unit. The gas inlet 70 is connected with a source of oxygen-free CO₂ or N₂ and the apparatus flushed out with a relatively large rate of flow of gas. The flow of gas at 70 is then reduced and the outlets 72 and 74 adjusted to permit a slow escape of gas from each. The melting unit is connected with a source of heating fluid, preferably from the same source as that used in heating the auxiliary heating shell.

The flakes of material directly in contact with the surface of melting unit 32 melt and the molten material drains to the container 34. As the flakes melt, more flakes come into contact with the melting surface and in turn melt, thereby insuring a constant supply of molten material. When the assembly has reached the proper temperature for the spinning of the particular polyamide, the gas inlets and outlets 70, 72 and 74 are closed and the inlet 52 and outlet 54 to the melting unit disconnected. The entire assembly is then lifted by means of the eye bolts

44 and transported to the already hot shell 1, in the spinning room, lowered into it and fixed in position by means of the bolts 22. The flow of gas through the apparatus is then reestablished by the proper connections and adjustments. The melting unit is again connected to the same source of heating fluid that enters the shell through inlet 10. The pump shaft 18 is then coupled with the pump mechanism to drive the pump 36.

Spinning is begun when the pump is in operation. The molten polyamide drawn from the container 34 by the pump 36 is metered to the spinning unit 38 from which it is extruded in the form of filaments. The extruded filaments are collected as a yarn bundle in an orderly manner.

When it is necessary to repair or adjust the assembly, it is only necessary to disengage the pump drive shaft, disconnect the gas and heating fluid connections, remove the nuts from the bolts 22, whereupon the whole assembly can be removed and replaced by another preheated unit. Delay is thereby reduced to a minimum. If desired, the solid flake need not be added until the unit is in the spinning position since melting is soon effected with the preheated unit.

While this invention has been described with particular reference to the melt spinning of polyamide filaments, yarns, ribbons and the like, it is not so limited. The apparatus has particular utility for the spinning of molten organic filament-forming compositions which are crystalline in the solid state as evidenced by X-ray investigation. In general, fiber-forming synthetic linear polymers (super-polymers) to which class the superpolyamides belong exhibit this property. Other types of synthetic linear polymers are polyesters, polyethers, polyacetals, mixed polyester-polyamides, etc., such as may, for example, be prepared by a condensation reaction as described in U. S. Patent No. 2,071,250. Fiber-forming polymers prepared by the high pressure polymerization of ethylene, which are more fully described in British Patent No. 471,590 are also crystalline in the solid state.

The invention is also applicable to the spinning of other molten organic filament-forming compositions such as the vinyl polymers, polystyrene and polyacrylic acid derivatives.

The filament-forming material used in the process of this invention may contain modifying agents, for example, lustre-modifying agents, plasticizers, pigments and dyes, anti-oxidants, resins, etc.

By a practice of this invention it is possible to melt spin filaments, yarns, ribbons and the like from organic filament-forming compositions economically and with a minimum of delay. It is possible to take full advantage of the space and facilities of the spinning area and to replace or repair defective units or to change the type of production without interfering with adjacent apparatus.

Since it is obvious that many changes and modifications can be made in the above-described details without departing from the nature and spirit of the invention, it is to be understood that the invention is not to be limited thereto, except as set forth in the appended claims.

I claim:

1. A melt spinning apparatus comprising a melting unit and a spinning unit, means connecting said two units securely to each other as a melting and spinning assembly, a heating shell, means for applying heat to said heating shell, the spinning unit of said melting and spinning as-

sembly adapted to fit snugly in said heating shell, and means, positioned on the exterior of said apparatus, for readily connecting and disconnecting said heating shell and said melting and spinning assembly.

5. 2. A melt spinning apparatus comprising a melting unit and a spinning unit, means connecting said two units securely to each other as a melting and spinning assembly, said spinning

unit provided with a flanged housing frame, a flanged heating shell, means for applying heat to said heating shell, said housing frame positioned, with a snug fit, within said heating shell, the flange of said housing frame resting on the flange of said heating shell, and readily disengagable means for fastening said flanges together.

CRAWFORD HALLOCK GREENEWALT.
